Attorney

UNITED STATES PATENT OFFICE.

FLORENCE G. LYLES, OF MUSKEGON, MICHIGAN.

SEWING CABINET.

Application filed August 22, 1925. Serial No. 51,854.

To all whom it may concern:

Be it known that I, FLORENCE G. LYLES, a citizen of the United States, residing at Muskegon, in the county of Muskegon and 5 State of Michigan, have invented certain new and useful Improvements in Sewing Cabinets, of which the following is a specification, reference being had to the accompanying drawings.

10 This invention relates to improvements in sewing cabinets and more particularly to a sewing cabinet especially adapted for use in conjunction with a sewing machine.

An important object of the invention is to 15 produce a device of this character having a catch trough structure capable of being positioned beneath the table of a sewing machine at the rear edge thereof to receive material passing from the table and prevent 20 the same from falling to the floor.

A further object of the invention is to 25 produce a device of this character in which the catch trough structure folds into a cabinet structure square in form and occupying

30 but little space.

A still further object of the invention is to produce in combination with a structure of the type above described a folding table structure of novel and improved design, 35 which may be used for ordinary hand sewing operations and which has means associated therewith for conveniently supporting patterns, spools of thread and similar accessories employed in sewing.

40 A further object of the invention is to provide a device of this character which is extremely compact when in its inoperative position, which may be readily and cheaply produced and which will be durable and efficient in service.

45 A further object of the invention is the production of a table structure having a folding leaf of novel means for supporting the leaf in both its extended and folded positions.

50 These and other objects I attain by the construction shown in the accompanying drawings, wherein for the purpose of illustration is shown a preferred embodiment of my invention and wherein:—

Figure 1 is a perspective view of a sewing cabinet constructed in accordance with my invention;

55 Figure 2 is a perspective of the opposite side of the cabinet, a portion being broken away to show the interior of the trough;

Figure 3 is a transverse sectional view, the trough being open and shown in position beneath the table of a sewing machine;

Figure 4 is a perspective of the cabinet 60 with the sewing table in position for use;

Figure 5 is a transverse vertical sectional view of the table in extended position;

Figures 6 and 7 are detailed sectional views taken through the table showing the 65 manner of holding the leaves thereof in extended and folded positions;

Figure 8 is a combined detached perspective of the spool holder and the latch therefor.

70 Referring now more particularly to the drawings, the cabinet includes a pair of leg supported standards 10 which extend transversely of the completed cabinet. These standards have connected thereto cabinet 75 ends 11 extending vertically and connected centrally by a vertically positioned longitudinally extending partition 12 which is disposed centrally of the completed cabinet. Between the end members 11, upper and 80 lower partitions 13 and 14 are disposed, these partitions being horizontally arranged and being each secured to the central partition 12. The lower partition 14 rests upon the upper surfaces of the leg supported standards 10 and the partitions 13 and 14 are arranged at the same side of the middle partition 12. The upper partition 13 is arranged approximately midway of the length 85 of this partition and forms the bottom for 90 a catch trough 15, hereinafter to be more fully described.

95 Hinged to the outer edge of the upper partition, as at 16, is a swinging panel 17, the upper edge of which, when the panel is vertically disposed, is arranged in the same plane as the upper edge of the central partition 12. In its vertical position, this panel fits between the outer edges of the end walls 11 above the partition 13. Pivoted to the 100 upper end of the central partition 12, as at 18, is a trough cover 19 which extends between the upper end of the panel 17 and the partition 12 and forms a cover for the trough 15 when in closed position. With the parts, 105 as illustrated in Figure 1 which shows the trough in its closed position, the cover 19 at its ends rests upon the upper ends of spaced ribs 20 and 21 carried by opposite ends of the panel 17 upon the inner face thereof. 110 The rib 20 is relatively narrow and has pivoted thereto a catch 22 adapted to coact

with an eye 23 carried by a swinging trough end 24 hinged, as at 25.

These trough ends 24 normally lie against the partition 12 and when it is desired to move the trough to open position, the panel 17, which is normally held closed by a hook 26 engaging an eye carried by the cover 19, is released and swung outwardly. The cover 19 is then thrown back and the trough ends 24 are swung outwardly so that they align with the space between the ribs 20, 21 at the ends of the panel. The panel is then moved upwardly until it engages the beveled free edge 27 of the trough ends 15 at which time the catches 23 are placed in position and the trough is ready for use.

In the construction of the device, the height of the trough edge is represented by the upper edge 28 of the panel 17 and when 20 in open position is made such that this panel will pass beneath the lower face of the table 29 of a sewing machine. Hinged to one of the partitions 13 or 14 and preferably to the partition 14, as at 30, is a door 31 having 25 a rotating pull knob 32 provided interiorly of the door with a catch 33 for engaging the other of the partitions. The space provided between the partitions 13, 14, the door 31 and partition 12 forms a closet 33^a for the 30 storage of articles, particularly uncompleted sewing. The opposite side of the partition 12 and at the upper edge thereof a longitudinally extending horizontal partition 34 is provided extending between the end 35 members 11 and upon this partition 34, which actually forms a top for this side of the cabinet the cover 19 rests when the trough is in open position. It will be obvious that the cover 19 and partition 34, when 40 the cabinet is not in use, combine to form a top for the cabinet. Spaced below the partition 34 and paralleling the same is a second and similar partition 35, these partitions combining to form therebetween a 45 drawer space having arranged therein a drawer 36 for the reception of spools, needles and the like. This drawer may be suitably compartmented, as indicated.

Pivoted to and depending from the partition 35 is a panel 37 swingable about the pivots 38 thereof to a horizontal position in which it forms a table. In this horizontal position, it is supported by pivoted brackets 39. Hinged to each end of the 55 table panel 37 is an extension leaf 40 foldable upon the inner face of the table panel 37 so that it is hidden from view when the table panel is vertically disposed. Secured to the leg supported standards 10 are stop 60 blocks 41 against which these folded leaves 40 engage to limit movement of the panel 37 when it is vertically disposed. This panel may be held in this position by a catch 42 pivoted to the lower end of the partition 12 65 and engaging an eye 43 on the free edge

of the panel 37. Longitudinally slideable upon the inner or under face of the panel 37 are leaf holders 44, each comprising an elongated bar operating between guides 45 and 46 carried by and spaced longitudinally of the under surface of the table panel and having at its opposite ends down-bent portions 47 and 48 for alternately engaging the guides 45 and 46 to limit the sliding movement of the support. Each support, when its bent end portion 48 engages the guide 46 is extended beyond the edge of the panel 37 and beneath the extended leaf 40 with which it is associated and when its stop 47 is engaged with its guide 45, has its bent end portion 48 so positioned that as the associated leaf 40 is swung upwardly to parallel the panel 37 it engages the free edge of the leaf and provides a resilient latch therefor.

The under surface of the table panel 37 has preferably secured thereto a spring holder 49 for convenience in holding a pattern or the like which is in constant use but which it is not desired to place upon the upper surface of the table. The partition 12 beneath the partition 35 has preferably secured thereto a case 50 for the reception of patterns and the like which are not to be put to immediate use. The upper surface 95 of the table structure is provided with a longitudinally extending series of graduations forming a rule for assistance in measuring and laying out cloth in cutting operations, these graduations being continued to 100 the extension leaves as shown at 51. The outer face of the panel is provided with a transversely extending groove 52 within which is arranged a spindle 53 pivoted at the sides of the groove and having an angular foot 54. Slidably arranged in guides carried by the table is a latch 55 which, when the spindle is vertically disposed, may be arranged over the angular foot to hold the spindle in its vertical position. This 105 spindle may be conveniently employed for holding a spool or spools of thread which are being used in the immediate sewing operation. At the upper and lower ends of the end walls 11 outwardly projecting ledges 115 56 and 57 are provided which may be conveniently employed for holding articles in constant use. It will, of course, be obvious that the table, as described, is capable of a certain range of change and modification and that many accessories may be applied thereto without in any manner departing from the spirit of my invention. It will also be obvious that a construction of this character may be relatively cheaply produced 120 and will be of the utmost convenience in the sewing room.

I claim:

1. In a sewing cabinet, a cloth receiving trough including side, top and bottom walls,

one of said side walls and bottom wall being stationary, the top and the remaining side wall being hingedly connected to said stationary side and bottom walls, end walls

5 for the trough being pivotally connected with one of said stationary walls, said hinged side wall adjacent each end thereof having spaced ribs adapted for the reception of the outer edges of the end walls when in operative position and means upon such side wall 10 engaging each end wall to prevent escape of the outer edges of the end walls from between said ribs.

2. In a sewing cabinet, a cloth receiving trough having one side wall thereof swingable outwardly from a vertical position where it combines with the remaining walls of the trough to form a closed receptacle to a position where it inclines outwardly and 15 upwardly and is positionable beneath the table of a sewing machine and foldable end walls positionable to bridge the space between the side walls of the trough when said movable side wall is in the last named 20 position.

3. In a sewing cabinet, a cloth receiving trough having one side wall thereof swingable outwardly from a vertical position where it combines with the remaining walls 30 of the trough to form a closed receptacle to a position where it inclines outwardly and upwardly and is positionable beneath the table of a sewing machine, foldable end walls positionable to bridge the space between the side walls of the trough when said 35 movable side wall is in the last named position and a top for said trough pivoted to permit uncovering of the entire top of the trough.

40 4. In a sewing cabinet, spaced leg supported standards, end walls secured to said standards, a central partition connecting the end walls and maintaining the same in spaced relation, horizontal partitions extending outwardly from the central partition intermediate the end walls at opposite 45 sides of said central partition dividing closet

and drawer room space, a table pivotally connected with one of said horizontal partitions at one side of the vertical partition 50 and means pivotally mounted upon said vertical partition and swingable to support the table in an operative position.

5. In a sewing cabinet, spaced leg supported standards, end walls secured to said standards, a central partition connecting the end walls and maintaining the same in spaced relation, horizontal partitions extending outwardly from the central partition intermediate the end walls at opposite sides 60 of said central partition dividing closet and drawer room space, a table pivotally connected with one of said horizontal partitions at one side of the vertical partition, means pivotally mounted upon said vertical 65 partition and swingable to support the table in an operative position, said table when in inoperative position combining with said end walls and horizontal partition to which it is pivoted and vertical partition to provide 70 a housing and receptacles for sewing accessories arranged within the housing.

6. In a sewing cabinet, spaced leg supported standards, end walls secured to said standards, a central partition connecting the 75 end walls and maintaining the same in spaced relation, horizontal partitions extending outwardly from the central partition intermediate the end walls at opposite sides of said central partition dividing closet 80 and drawer room space, a table pivotally connected with one of said horizontal partitions at one side of the vertical partition, means pivotally mounted upon said vertical 85 partition and swingable to support the table in an operative position, means upon the leg supported standards against which the table engages to limit its movement to inoperative position and means for connecting said vertical partition and table to maintain the table in inoperative position.

In testimony whereof I hereunto affix my signature.

FLORENCE G. LYLES.
